PADDLE WHEEL BOAT

Horace H. Roby, 923 E. Catalpa, Springfield, Mo.

Filed Sept. 24, 1959, Ser. No. 57,665

Term of patent 14 years

(Cl. D71—1)

Fig. 1 is a top plan view of a paddle wheel boat embodying my new design;

Fig. 2 is a rear elevational view of same;

Fig. 3 is a side elevational view of same;

Fig. 4 is a front elevational view of same; and

Fig. 5 is a fragmentary sectional view taken along the line 5—5 of Fig. 3 in the direction of the arrows.

The side not shown is substantially the same as the side shown.

I claim:

The ornamental design for a paddle wheel boat, substantially as shown and described.
